UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO.

SALES-BOOK.

1,068,214.

Specification of Letters Patent. Patented July 22, 1913.

Application filed November 4, 1911. Serial No. 658,485.

To all whom it may concern:

Be it known that I, EDWARD KIRBY BOTTLE, a citizen of the United States, residing at Elmira, in the county of Chemung and State of New York, have invented certain new and useful Improvements in Sales-Books, of which the following is a full, clear, and exact description, such as will enable others skilled in the art to which it appertains to make and use the same.

This invention relates to sales books.

One of the objects of this invention is to provide a simple and practical form of sales book which will be inexpensive to manufacture.

Another object is to provide a self-contained sales book of the above character which will be durable in construction.

A further object is to provide a sales book of the above type permitting rapid manipulation of the leaves in recording transactions in duplicate.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing, wherein is shown one of the various possible embodiments of my invention, Figure 1 is a perspective view showing a sales book in operative position; Fig. 2 is a longitudinal sectional view of the sales book; Fig. 3 is a detail view showing one side of the web forming the leaves of the pad.

Similar reference characters refer to similar parts throughout the several views of the drawing.

Referring to the drawing in detail, a back 1 forms the bottom cover of the sales book and has connected therewith by means of a flexible hinge 2, a top cover 3 adapted to be folded over to inclose a salesbook pad. This pad comprises a plurality of sets of original and duplicate leaves, 4 and 5 respectively, made in what is known as the continuous fold or zigzag form. It is mounted directly upon the back or support 1 in any desired manner. The back of each original leaf is carbonized over substantially its entire reverse surface or that part of the

surface opposite to the space upon which the duplicate of the transaction is recorded. This carbonized portion is indicated at 6 on the turned back corner of the original leaf 4, but is shown more fully in the detail view 60 Fig. 3.

Interposed beneath the two uppermost sets of leaves, each set being constituted by an original and duplicate sheet, is positioned a thin metallic plate 7, adapted to prevent any transaction being recorded on the second set of leaves. By making this plate of metal it will resist the transmission of records under any reasonable pressure. It will also be more durable. This plate 7 70 is hinged along its lower edge 8 to a transverse connecting portion of spring arms 9 having their ends 10 firmly secured in the back or support 1. This transverse portion is provided with a central turned-in section 75 11 adapted to engage and hold the lower end of the sets of leaves in their folded position, thus temporarily binding the leaves and preventing them from streaming or becoming unfolded if the book should be 80 accidentally dropped.

At the opposite end of the sets of leaves is a second holding member 12 comprising a flat band connecting the free ends of arms 13 mounted on each side of the pad, having 85 their opposite ends firmly secured to the back 1. Both of these holding means are so positioned and arranged as to press downwardly upon the ends of the sets of leaves under the action of the spring arms, 90 thereby automatically accommodating themselves at all times to the pad as it becomes gradually reduced in thickness on the removal of the sets of leaves.

The operation of this device is substantially as follows: After arranging the pad in substantially the position shown in Fig. 1 of the accompanying drawing, the transaction is recorded upon the original leaf 4 and reproduced through the manifolding 100 material 6 upon the duplicate leaf 5. After recording the transaction, the top of the original leaf 4 is grasped by the right hand of the operator and pulled up and rearwardly, thereby separating the top edge of 105 the next original sheet from the holder, 12. By this movement the plate 7 is automatically removed from its position on top of the second original leaf so that it swings downwardly by gravity about its hinged edge 8 110

onto the cover 3. A further movement of the web removes the next original leaf from the lower holder 11. The plate 7 is then swung upwardly over the pad to lie under this next set of leaves when folded thereupon. The first set is then severed along the perforated lines at the top of the pad separating the top edge of the next original sheet and the bottom edge of the first duplicate sheet. The book is then ready for the second operation. The set of leaves after being removed from the pad may be temporarily laid aside, and if it is subsequently decided to add an item to that transaction it is unnecessary to rearrange the leaves with relation to a carbon sheet as the manifolding material is already in operative position to permit a further transaction to be recorded in duplicate.

20 It is thus seen that this invention provides a simple and inexpensive form of sales book, accomplishing, among others, all of the objects above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters

35 Patent is:

1. In a manifolding sales book, in combination, a pad comprising a continuously folded web adapted to form a plurality of sets of original and duplicate leaves, manifolding means between the leaves of each set, means adjacent one end of the book adapted to accommodate itself to the pad as its thickness diminishes and adapted to temporarily bind the ends of said sets of leaves to prevent streaming, and means connected with said first mentioned means adapted to be inserted beneath the top set of leaves to prevent manifolding on the lower sets of leaves.

50 2. In a manifolding sales book, in combination, a pad having a continuously folded sheet forming a plurality of sets of consecutively arranged original and duplicate leaves foldably connected together, the back of each original leaf being carbonized whereby the record is transferred to the duplicate sheet.

3. In a manifolding sales book, in combination, a pad having a continuously folded sheet forming a plurality of sets of consecutively arranged original and duplicate leaves foldably connected together, the back of each original leaf being carbonized whereby the record is transferred to the duplicate sheet, and having means adapted to be in-

terposed beneath the top set of leaves to prevent the record being transferred to an underneath set.

4. In a manifolding sales book, in combination, a pad having a continuously folded sheet forming a plurality of sets of consecutively arranged original and duplicate leaves foldably connected together, the back of each original leaf being carbonized whereby the record is transferred to the duplicate sheet, and having a plate adapted to be interposed between the two upper sets of leaves to prevent the record being recorded on the lower set.

5. In a manifolding sales book, in combination, a pad comprising a plurality of sets of original and duplicate leaves, respectively connected at their ends and folded in zig-zag form the back of each original leaf being carbonized for transferring the record to the duplicate sheet, and means for temporarily binding the ends of the sets of leaves.

6. In a manifolding sales book, in combination, a pad comprising a continuously folded sheet forming a plurality of sets of original and duplicate leaves, manifolding means between the leaves of each set spring means temporarily binding the ends of said sets of leaves to prevent the pad from streaming, and means connected with said spring means adapted to be interposed between the sets of leaves to prevent manifolding on a lower set.

7. In a manifolding sales book, in combination, a pad of zigzag form providing a plurality of sets of original and duplicate leaves, the back of each original sheet being carbonized whereby the transaction is recorded on said duplicate sheet, means at both ends of said sets of leaves adapted to temporarily hold the leaves in position but permit the leaves to be withdrawn therefrom, and a plate hinged at one end to one of said means adapted to be placed beneath the top set of leaves.

8. In a manifolding sales book, in combination, a pad of zigzag form providing a plurality of sets of original and duplicate leaves, the back of each original sheet being carbonized whereby the transaction is recorded on said duplicate sheet, and means at both ends of said sets of leaves adapted to temporarily hold the same in position but permit the leaves to be withdrawn therefrom, said means being spring pressed whereby they accommodate themselves to the pad as its thickness is reduced.

9. In a manifolding sales book, in combination, a pad of zigzag form providing a plurality of sets of original and duplicate leaves, manifolding means associated therewith, means at both ends of said sets of leaves adapted to temporarily hold the same in position but permit the leaves to be with-

drawn therefrom, said means being spring pressed whereby they accommodate themselves to the pad as its thickness is reduced, and means secured to one of said holding means adapted to be inserted between the top set of leaves to prevent the transaction being recorded on a lower set.

10. In a manifolding sales book, in combination, a pad comprising a plurality of sets of original and duplicate leaves, manifolding means connected therewith, holding means at the lower end of said pad adapted to prevent the pad from streaming, a member connected with said holding means adapted to be interposed beneath the upper set of the leaves to prevent the transaction from being recorded on a lower set.

11. In a manifolding sales book, in combination, a pad comprising a plurality of sets of original and duplicate leaves, manifolding means connected therewith, holding means at the lower end of said pad adapted to prevent the pad from streaming, a member connected with said holding means adapted to be interposed beneath the upper set of leaves to prevent the transaction from being recorded on a lower set, said holding means being spring-actuated whereby it

automatically accommodates itself to the gradual reduction in thickness of the pad. 30

12. In a manifolding sales book, in combination, a support, a continuously folded pad mounted thereon, comprising a plurality of sets of original and duplicate leaves, the back of each original leaf being 35 carbonized whereby the record is transferred to said duplicate leaf, holding means connected by a spring arm with said support, adapted to engage one end of said sets of leaves, a member mounted on said support, 40 adapted to be interposed beneath the top set of leaves to prevent the transaction being recorded on a lower set, and a second holding means connected by a spring arm with said back engaging the other end of 45 said sets of leaves, said sets of leaves being perforated at their ends whereby they may be separated from each other and from the pad.

In testimony whereof I affix my signature, in the presence of two witnesses.

EDWARD KIRBY BOTTLE.
